MACHINE FOR PRESSING THE BOTTOMS
OF SHOES

James P. Fredericksen, Wollaston, Mass., assignor
to United Shoe Machinery Corporation, Paterson, N. J., a corporation of New Jersey

Application December 12, 1933, Serial No. 702,011

33 Claims. (Cl. 12—51)

This invention relates to machines for pressing the bottoms of shoes, and in some aspects more particularly to machines for pressing the bottoms of welt shoes after attachment of the 5 welt but before the outsole is applied to the shoe. The invention is accordingly herein illustrated and described with special reference to an operation of that character, although it will be recognized that in various aspects it is not thus limited in its applicability.

In the manufacture of welt shoes it is sometimes the practice, after the welt-sewing and inseam-trimming operations, to apply compacting pressure to the inseam materials, i. e., the 15 parts of the welt, upper and insole that are directly connected together by the inseam stitches, preparatory to the laying of the outsole. This permits the outsole to be applied in closer relation to the insole and upper and contributes also 20 in other ways to better results in the manufacture of the shoe. For thus pressing the inseam materials there have been utilized to some extent machines of the same general character as commonly used for leveling outsoles with rolling pressure, characteristic features of which are disclosed, for example, in Letters Patent No. 1,667,761, granted on May 1, 1928, upon an application of E. E. Winkley and H. A. Davenport. In the operation of such a machine the shoe- 25 pressing roll is moved downwardly into contact with the toe end of the shoe bottom when the latter is under the roll, after which the roll traverses the forepart and shank portions of the shoe bottom with its axis in a substantially horizontal position generally parallel to the shoe bottom. Thereafter the roll operates along the opposite sides of the shoe bottom successively while held in such positions that its axis is inclined laterally of the shoe.

An object of the present invention is to provide 30 improved means for pressing shoe inseam materials whereby better results may be obtained than by the use, for example, of a machine operating as above described. For the purposes in view the machine herein shown is provided with a pair of pressing rolls arranged to operate respectively at the opposite sides of the shoe bottom, the rolls being relatively movable heightwise of the shoe so as to assume positions determined by the contour of the shoe bottom and thus to apply adequate pressures to the inseam materials at the opposite sides of the shoe bottom while operating along both sides simultaneously. To permit such relative movements of 35 the rolls they are carried, in the construction

shown, by arms which are mounted for swinging movements heightwise of the shoe, and the rolls are pressed down on the shoe bottom by different springs associated respectively with the different arms and each adjustable as to stress 5 independently of the other.

In operating upon the inseam materials it is desirable to press them not only heightwise of the shoe, but also in directions inwardly from the edge of the shoe bottom, in order to improve 10 such conditions as may have resulted from outward pull on the lip of the insole in the earlier lasting and welt-sewing operations; and in another aspect the present invention provides improved means for accomplishing this result. For 15 the purpose in view the construction herein shown is such that the rolls as they first traverse the shoe bottom act on the inseam materials at the end of the toe and along the sides of the shoe bottom rearwardly of the toe end with pressures directed both heightwise of the shoe and inwardly from the edge of the shoe bottom. More particularly, as illustrated, the rolls are so arranged as to act on the inseam materials first 20 at the end of the toe with inwardly directed pressure and to be lifted by the action of the shoe thereon while pressing the materials heightwise of the shoe, after which the rolls act on the materials along the sides of the shoe bottom at the rear of the toe end with pressures directed both 25 heightwise of the shoe and inwardly from the edge of the shoe bottom. To render the rolls effective in this manner along the sides of the shoe bottom, they are so formed as to increase progressively in diameter toward their outer 30 ends and are so mounted as to permit them to be wedged apart by the action of the shoe thereon against the resistance of spring means that constantly urges them inwardly toward 35 each other. To permit such movements of the rolls toward and from each other, their supporting arms, mounted as above described for swinging movements heightwise of the shoe, are also supported for swinging movements relatively to 40 each other widthwise of the shoe; and for better accomplishment of the objects in view the construction shown is further such that initially the rolls are positioned in axial alignment 45 with their inner ends in contact with each other for operation on the inseam materials at the end of the toe. By this organization the inseam materials are pressed inwardly in a more satisfactory manner than by machines operating as heretofore, in the manner above described, to 50 55

press them first heightwise of the shoe by the action of a single horizontal roll and thereafter to apply more or less inwardly directed pressure by the action of the roll in inclined relation to the shoe bottom.

The above and other features of the invention, including novel means for alining the rolls properly with the shoe lengthwise of the shoe, novel means whereby the rolls may be adjusted properly in relation to the shoe bottom, and various novel details of construction and combinations of parts, will now be more particularly described by reference to the accompanying drawings and pointed out in the claims.

15 In the drawings,

Fig. 1 is a view in right-hand side elevation of a machine in which the invention is embodied, with parts broken away, showing the machine as it appears in operating on a shoe;

20 Fig. 2 is a plan view on a larger scale of a portion of the structure shown in Fig. 1, with parts broken away;

Fig. 3 is a section on the line III—III of Fig. 2;

25 Fig. 4 is a view similar to Fig. 2 of a portion of the structure there shown, but illustrating the positions of the parts as the rolls begin their operation at the end of the toe;

30 Fig. 5 is a side elevation of the parts shown in Fig. 4, with one of the rolls omitted and a portion of its supporting arm broken away; and

Fig. 6 is a right-hand side elevation similar to a portion of Fig. 1, but illustrating the use of a saddle between the leveling rolls and the shoe.

35 Machines of the well-known type illustrated are twin machines, having two sets of operating instrumentalities for operating respectively on shoes in different locations in the machine. Portions of only one of these two sets of instrumentalities are shown in the drawings, since they are substantially alike, and only such parts of that set as it is necessary to refer to for an understanding of the invention will be hereinafter mentioned.

40 For supporting a shoe in position for the bottom pressing operation machines of the illustrated type are provided with a shoe support or jack comprising a toe post 10 and a heel post 12 which are relatively adjustable for shoes of different lengths. The toe post 10 carries a toe rest 14 for supporting the toe end of the shoe, and pivotally mounted on the heel post 12 is a block 16 which carries a spindle 18 arranged to enter the spindle hole of the last. Through 45 connections including a link 28 the block 16 and its spindle 18 are tipped by a hand lever 22 to jack the last and shoe firmly upon the toe rest 14, as more fully disclosed in Letters Patent No. 1,719,158, granted on July 2, 1929 upon an application of E. E. Winkley and H. A. Davenport.

50 The jack as a whole is mounted for swinging movements in directions lengthwise of the shoe on a rockshaft 24, and such movements are imparted to the jack by automatic operating means to cause the pressing rolls hereinafter described to traverse the forepart and shank portions of the shoe bottom. This operating means is of substantially the same character as disclosed in 55 Letters Patent No. 1,239,664, granted on September 11, 1917 upon an application of W. C. Baxter, and includes an operating lever 26 connected by a link 28 to another lever 30 which is pivoted at 32 on the frame of the machine, the lever 30 60 in the construction herein shown carrying a roll

34 engaged by a path cam 36 carried as heretofore by a cam disk 38 fast on a cam shaft 40. Secured to the cam disk 38 is a worm wheel 42 engaged by a worm 44 on a shaft 46 which is operated through a clutch 48. Associated with 5 the clutch 48 is clutch-controlling mechanism including a shipper rod 50 movable toward the left (Fig. 1) to connect the parts of the clutch and toward the right to disconnect them and stop the machine. Stopping of the machine is 10 effected automatically by a member 52 carried by the worm wheel 42 and arranged to engage a roll 54 carried by a plate 56 which is mounted to swing about a stud 58 and has a finger 60 arranged to engage an arm 62 fast on the rod 50. 15 When the member 52 thus engages the roll 54 the plate 56 is swung against the resistance of a spring 64 and acts on the arm 62 to move the rod 50 to the right and thus to stop the machine. The starting of the machine is effected by a 20 treadle, not shown, which rocks the rod 50 and the arm 62 and thus carries the arm out of engagement with the finger 60, whereupon a spring 66 moves the rod 50 to the left to start the machine. This controlling mechanism is constructed 25 substantially as heretofore in machines of the illustrated type, except that as herein shown there are two diametrically opposite members 52 for stopping the machine at the end of each half revolution of the cam disk 38 for reasons 30 hereinafter explained. In machines of the type referred to the jack is swung initially inward by the operator to a position where it is connected to the jack-operating means by a pin 68, as disclosed in the previously mentioned Letters Patent 35 No. 1,239,664, and just before the machine comes to a stop mechanism controlling this pin is operated by a member 70 on the cam disk 38 to disconnect the jack from its operating means. Since there are two members 52 in the machine 40 herein shown for stopping the machine at the end of each half revolution of the cam disk 38, as above explained, there are likewise two members 70 for releasing the jack as required substantially at the times when the corresponding members 52 45 become operative to disconnect the parts of the clutch.

For purposes of this invention there are provided two rolls 12 (Fig. 2) arranged to operate respectively at the opposite sides of the shoe bottom, each of these rolls having a pressing face curved widthwise of the shoe and each roll increasing progressively in diameter from its inner end outward. These rolls are rotatably mounted on studs 74 which are fastened to arms 76 so that 55 the axes of the rolls are at all times in fixed relation to the arms, ball bearings 78 being provided between the rolls and the studs, as indicated in Fig. 2. Each roll is held on its stud 74 by a washer 79 (Fig. 5) and a screw 80. The 60 arms 76 are mounted independently of each other for swinging movements heightwise of the shoe on pins 81 supported on brackets 82, and these brackets are mounted for swinging movements on pins 84 extending heightwise of the shoe and 65 supported by a member 86. The member 86 is a sleeve member fastened on the forward end of a rod 88 which serves as a roll carrier and is mounted to turn in a holder 90, this holder being provided with trunnions 92 whereby it is mounted 70 for swinging movements in directions heightwise of the shoe. Fastened to the rod 88 within a recess in the holder 90 is a sleeve 94 which by engagement with the holder prevents lengthwise movements of the rod 88. The sleeve 94 is pro- 75

vided with lugs 96 in which are threaded screws 98 arranged to bear at their lower ends on the holder 90. The screws 98, therefore, prevent turning movement of the rod 88 and of the rolls 5 72 about the axis of the rod in the operation of the machine on a shoe, but afford provision for adjustment of the rod and the rolls about this axis.

It will be evident that the roll-carrying arms 10 76 may swing with the brackets 82 in directions widthwise of the shoe above the axes of the pins 84. The arms are controlled by a spring 100 (Figs. 2 and 4) which is connected to them at its opposite ends and tends to swing them inwardly 15 toward each other. Initially the inner ends of the rolls 72 are held in contact with each other (Fig. 4) by the spring 100, the rolls being then preferably in axial alinement, and against the resistance of the spring 100 the rolls are forced 20 apart more or less by the wedging action of the shoe thereon, especially the action of the wider forepart portion of the shoe, as illustrated in Fig. 2. To avoid danger of damaging a shoe such as might result from sudden lateral and down- 25 ward swinging of the arms 76 in case the spring 100 should break, there is provided a rod 102 extending through lugs 104 on the arms and having nuts on its ends to engage the lugs and prevent such accidental swinging apart of the arms 30 as to permit the rolls to be forced downward over the sides of the shoe.

In order to aline the rolls 72 properly with the shoe lengthwise of the shoe the brackets 82 are further controlled by a coil spring 106. This 35 spring encircles a rod 108 which extends loosely through openings formed in arms 110 fastened to the upper ends of the brackets 82. The spring 106 presses at one end on a flat plate 112 which is slidably mounted on the rod 108 and is arranged to engage the flat inner face of the adjacent arm 110, this plate having integral therewith a sleeve 114 extending within the coil spring 106 to assist in guiding the plate in any movement of the latter lengthwise of the rod 108. At 40 its opposite end the spring 106 bears on a washer 116 which abuts against a nut 118 on the rod 108. Also threaded on the rod 108 is another nut 120 which serves as an abutment for a flat plate 122 arranged to engage the inner flat face of the other arm 110, this plate having a sleeve portion 124 extending therefrom loosely through the opening in the arm 110 to assist in holding the plate against any tipping movement relatively to the rod 108. It will thus be seen that 45 the spring 106 tends by expansion to force the plates 112 and 122 apart and that these plates by their pressure on the arms 110 tend to maintain these arms and the brackets 82 to which they are fastened in such positions that the 50 plates are flat against the inner faces of the arms 110, at which time the arms 76 are in such positions that the rolls 72 are in proper initial alinement with the shoe lengthwise of the shoe. When the rolls 72 are forced apart by the wedging action of the shoe thereon the plates 112 and 55 122 are forced more or less inwardly toward each other against the resistance of the spring 106 by the turning movements of the arms 110, as illustrated in Fig. 2, the plates assuming positions 60 in which they are more or less out of parallelism with the adjacent faces of the arms 110. It will be evident, therefore, that these plates and the other parts of the controlling mechanism described permit such lateral swinging movements 65 70 of the arms 76, either in opposite directions or

in the same direction, that the rolls 72 may during the pressing operation assume positions determined by the contour of the shoe, and that they insure return of the rolls to predetermined positions widthwise of the shoe when the shoe 5 leaves the rolls. It will also be evident that the spring 100 assists the spring 100 in forcing the arms 76 inwardly toward each other.

The provision for swinging movements of the arms 76 independently of each other heightwise 10 of the shoe about the axes of the pins 84, as hereinbefore described, permits the rolls 72 to move relatively to each other heightwise of the shoe under control of the shoe so that the pressure applied to the shoe by either roll is unaffected by the position of the other roll, the axes of the rolls being at all times perpendicular to the directions of such movements of the rolls. Each arm 76 is under the influence of a separate spring 126 which tends to swing the arm downwardly and thus presses the roll 72 upon the bottom of the shoe. The lower end of each spring 126 is held against displacement by a stud 128 projecting within it, and within the upper end of the spring is a similar stud 130 projecting 20 downwardly from a disk 132 in a depression in which is seated the lower end of a screw 134. This screw is threaded in the arm 110 and may be turned by a hand wheel 136 to adjust the compression of the spring 126, a lock nut 138 being 25 provided to hold the screw in adjusted position. It will thus be seen that the downward pressure of each roll 72 on the shoe may be varied independently of the pressure of the other roll. To limit downward swinging movement of each arm 30 35 76 when no shoe is in contact with the rolls 72, each arm has a downwardly projecting finger 140 in which is threaded a screw 142 arranged to contact with the bracket 82. By adjustments of the screws 142 the initial positions of the two rolls 72 40 heightwise of the shoe may be varied independently of each other.

To assist in holding the rolls 72 upon the shoe bottom with adequate downward pressure there is further provided a spring 144 controlling the 45 holder 90 and the rod 88, this spring bearing at its lower end on a lever 146 which is pivoted at 148 to the frame of the machine and is connected by a link 150 to the holder 90. The upper end of this spring bears on a disk 152 engaged by 50 the lower end of a screw 154 which is threaded in a sleeve 156 slidably movable vertically in a portion of the frame of the machine. Bearing on lugs formed on the sleeve 156 near its upper end is the forked end of a lever 158 pivotally mounted 55 on a pin 160 on the frame, this lever being held stationary in a position adjustably determined by a screw 162 which is threaded in the lever and bears on the frame. By means of a hand wheel 164 fast on the screw 154 the screw may be turned 60 to vary the compression of the spring 144 and thus to vary the amount of pressure of the rolls 72 on the shoe bottom. It will be understood that the spring 144 thus acts equally on both the rolls through the previously-mentioned springs 126, 65 but that the two springs 126 may be adjusted independently of each other as hereinbefore explained to vary the pressures applied by the different respective rolls. Downward swinging movement of the holder 90 is limited by a screw 70 75 75 (Fig. 3) which is threaded in the frame and engages the lower face of the holder. This screw and the two screws 142 are preferably so adjusted that as the shoe is first swung inwardly by the jack the rolls 72 engage the inseam materials in-

itially at the extreme end of the toe with pressure directed inwardly from the edge of the shoe bottom and are lifted more or less by the pressure of the shoe upon them against the resistance of the springs 126 and 144 so that adequate downward pressure is applied through the springs to the inseam materials from the extreme toe end of the shoe to the rear ends of the inseam during the swinging movements of the jack.

10 In the operation of the machine, the operator first mounts a shoe on the spindle 18 and by depression of the lever 22 jacks the shoe on the toe rest 14. He then swings the jack inwardly until it is locked to the jack-operating mechanism by the pin 68, and thereafter actuates the clutch to start the machine in operation. The cam 36 is so shaped as to impart to the jack first an inward swinging movement such as to cause the rolls 72 to traverse the bottom of the shoe from the end of the toe to the rear ends of the inseam materials, then comparatively short swinging movements first outwardly and then inwardly to cause the rolls to traverse the shank portion of the shoe bottom repeatedly, and thereafter an outward swinging movement to cause the rolls to return to the toe end of the shoe and to leave the shoe, such movements being effected in the course of a half-revolution of the cam disk 38. Since the rolls operate simultaneously at both sides of the shoe bottom, these movements are sufficient to accomplish the results required, and accordingly the machine is stopped at the end of each half revolution of the cam disk as hereinbefore explained, the jack being released from its operating mechanism by the action of the finger 70 on means that controls the locking pin 68. As the rolls first traverse the shoe bottom they act initially on the inseam materials at the end of the toe with pressures directed both heightwise of the shoe and inwardly from the edge of the shoe bottom (Figs. 4 and 5) and then act progressively on the inseam materials along the forepart and shank portions of the shoe bottom with pressures also directed both heightwise of the shoe and inwardly. In the course of their operations on the shoe the rolls are forced more or less apart against the resistance of the spring 100 by the wedging action of the shoe thereon, especially the wider forepart portion of the shoe (Figs. 1 and 2), and the inwardly directed pressures of the rolls on the inseam materials along the sides of the shoe bottom are due both to the action of the spring 100 and to the fact that the rolls increase in diameter from their inner ends outward. It will be seen that as the tension of the spring 100 is increased by outward swinging movement of either roll, the spring tends with such increased tension to swing the other roll in the same direction, i. e., inwardly; and this assists in insuring that both rolls will assume proper positions corresponding to the lateral "swing" of the right or left last as they traverse the shoe bottom.

Instead of directly engaging the inseam materials, the rolls may, if the condition of the work renders it desirable, act upon the materials through a flexible saddle 168 (Fig. 4). This saddle may be made of leather and constructed, for example, as disclosed in Letters Patent No. 1,644,971, granted on October 11, 1927 upon an application of E. E. Winkley and H. A. Davenport, and the hand lever 22 may be used to apply the saddle to the shoe instead of tipping the last pin 18, as more fully disclosed in the previously mentioned Letters Patent No. 1,719,158. It will be under-

stood that when the saddle is used the rolls 72 act in all respects in the same manner as hereinbefore described except that they apply their pressures to the inseam materials through the saddle instead of by direct engagement with the materials.

Having described the invention, what I claim as new and desire to secure by Letters Patent of the United States is:

1. In a machine for pressing the bottoms of welt shoes after attachment of the welt but before the outsole is applied, the combination with a shoe support, of a pair of rolls for pressing the shoe inseam materials respectively at the opposite sides of the shoe bottom in response to relative movement of said shoe support and the rolls lengthwise of the shoe before the outsole is placed on the shoe, a holder supporting said rolls, and means arranged to act by engagement with said holder to position the rolls in such relation to the shoe as to cause them to act first on said inseam materials across the extreme end of the toe with pressures directed inwardly from the edge of the shoe bottom and to be lifted by the action of the shoe thereon while pressing said materials heightwise of the shoe, said rolls being constructed and arranged to act thereafter on the inseam materials progressively along the opposite sides of the shoe bottom simultaneously at the rear of the toe end with pressures directed both heightwise of the shoe and inwardly from the edge of the shoe bottom.

2. In a machine for pressing the bottoms of welt shoes after attachment of the welt but before the outsole is applied, the combination with a shoe support, of a pair of rolls arranged end to end for pressing the shoe inseam materials respectively at the opposite sides of the shoe bottom in response to relative movement of said shoe support and the rolls lengthwise of the shoe before the outsole is placed on the shoe, said rolls being yieldingly movable relative to each other widthwise of the shoe under control of the shoe from initial positions in contact with each other and being so formed and so positioned relatively to the shoe as to apply to the inseam materials all around the toe and along the sides of the shoe bottom rearwardly of the toe end pressures directed both heightwise of the shoe and inwardly from the edge of the shoe bottom as the rolls first traverse the shoe bottom.

3. In a machine for pressing the bottoms of welt shoes after attachment of the welt but before the outsole is applied, the combination with a shoe support, of a pair of rolls arranged to operate respectively at the opposite sides of the shoe bottom to press the inseam materials before the outsole is placed on the shoe, said rolls being yieldingly movable relatively to each other both heightwise and widthwise of the shoe and of greater diameter at their outer ends than at their inner ends, and means for positioning the rolls in such relation to the shoe as to cause them to act first on the inseam materials all across the end of the toe with pressures directed both heightwise of the shoe and inwardly from the edge of the shoe bottom and thereafter to be forced apart by wedging action of the shoe thereon while applying to the inseam materials along the sides of the shoe bottom pressures also directed both heightwise of the shoe and inwardly from the edge of the shoe bottom.

4. In a machine for pressing the bottoms of welt shoes after attachment of the welt but before

the outsole is applied, a shoe support movable to carry a shoe lengthwise, a pair of rolls arranged to operate respectively at the opposite sides of the shoe bottom before the outsole is placed on the shoe to apply pressure progressively to the shoe inseam materials, said rolls being yieldingly movable heightwise of the shoe in response to pressure of the shoe thereon, and means for positioning said rolls at such a height as to cause them to be lifted by the shoe in acting initially on the inseam materials at the end of the toe as the shoe support is moved to carry the shoe under the rolls, said rolls being of greater diameter at their outer ends than at their inner ends and mounted for movements away from each other in response to wedging action of the shoe thereon as the shoe is carried farther under the rolls.

5. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials at the opposite sides of the shoe bottom simultaneously upon relative movement of the shoe support and the rolls lengthwise of the shoe, and means for positioning said rolls initially with their inner ends in substantially contiguous relation to each other for operation on the inseam materials all across the end of the toe, said means being yieldable to permit the rolls thereafter to be forced apart by pressure of the shoe thereon.

6. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials upon relative movement of the shoe support and the rolls lengthwise of the shoe, said rolls being of greater diameter at their outer ends than at their inner ends, members carrying said rolls and mounted for movements relatively to each other widthwise of the shoe, and spring means arranged to position said members initially with the inner ends of the rolls in substantially contiguous relation to each other for operation on the inseam materials all across the end of the toe and yieldable to permit the rolls thereafter to be forced apart by wedging action of the shoe thereon.

7. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials upon relative movement of the shoe support and the rolls lengthwise of the shoe, arms carrying said rolls and mounted for swinging movements relatively to each other widthwise of the shoe, and spring means arranged to position said arms initially with the inner ends of the rolls in contact with each other for operation on the inseam materials at the end of the toe and yieldable to permit the arms thereafter to be swung apart by pressure of the shoe on the rolls.

8. In a machine for pressing the bottoms of welt shoes after attachment of the welt but before the outsole is applied, the combination with a shoe support, of a pair of rolls arranged to operate respectively at the opposite sides of the

shoe bottom before the outsole is placed on the shoe to apply pressure progressively to the shoe inseam materials upon relative movement of the shoe support and the rolls lengthwise of the shoe, members carrying said rolls and mounted for movements relatively to each other both heightwise and widthwise of the shoe, and spring means arranged to position said members initially with the rolls substantially in axial alignment with each other and in contact with each other at their inner ends and yieldable to permit the relative movements of the members with the rolls under control of the shoe.

9. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials upon relative movement of the shoe support and the rolls lengthwise of the shoe, said rolls being of greater diameter at their outer ends than at their inner ends, members carrying said rolls and mounted for movements relatively to each other both heightwise and widthwise of the shoe, spring means arranged to position said members initially with the rolls substantially in axial alignment with each other and in substantially contiguous relation to each other at their inner ends, said spring means being yieldable to permit relative movements of the members with the rolls heightwise of the shoe and also to permit the rolls to be forced outwardly away from each other by wedging action of the shoe thereon, and means for determining such initial positions of said members as to cause the rolls to act first on the inseam materials at the end of the toe with pressure directed inwardly from the edge of the shoe bottom and to be lifted by the action of the shoe thereon while pressing said materials heightwise of the shoe.

10. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials upon relative movement of the shoe support and the rolls lengthwise of the shoe, said rolls being mounted for movements relatively to each other widthwise of the shoe and being of greater diameter at their outer ends than at their inner ends to render the shoe effective to force them outwardly away from each other, and a spring controlling both rolls arranged to be subjected to increased stress by such outward movement of either roll and tending with such increased stress to impart inward movement to the other roll.

11. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials upon relative movement of the shoe support and the rolls lengthwise of the shoe, arms supporting said rolls and mounted for swinging movements relatively to each other widthwise of the shoe to permit the arms and the rolls to be forced outwardly away from each other by pressure of the shoe on the rolls, and

a spring arranged to be subjected to increased stress by outward movement of either arm and tending with such increased stress to impart inward movement to the other arm.

- 5 12. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials upon relative movement of the shoe support and the rolls lengthwise of the shoe, arms supporting said rolls and mounted for 10 swinging movements widthwise of the shoe, the rolls being of greater diameter at their outer ends than at their inner ends to cause them to be forced apart with the arms by wedging action of portions of the shoe thereon, and spring means 15 arranged to maintain both arms initially with the rolls in proper alignment with the toe end of the shoe lengthwise of the shoe and yieldable to permit the arms to swing under control of the shoe as determined by the contour of the shoe.
- 20 13. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials upon relative movement of the shoe support and the rolls lengthwise of the shoe, arms supporting said rolls and mounted for 25 swinging movements widthwise of the shoe, the rolls being of greater diameter at their outer ends than at their inner ends to cause them to be forced apart with the arms by wedging action of portions of the shoe thereon, a spring against 30 the resistance of which the arms are thus forced apart, and additional spring means for insuring return of both arms to predetermined positions widthwise of the shoe after operating on the shoe.
- 35 14. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials at the opposite sides of the shoe bottom simultaneously upon relative movement of the shoe support and the rolls lengthwise of the shoe, said rolls being supported for 40 swinging movements relatively to each other in directions heightwise of the shoe with their axes at all times perpendicular to such directions of movement, and spring means arranged to swing 45 said rolls in directions to press them upon the inseam materials while permitting them to yield each relatively to the other in response to pressure of the shoe upon them.
- 50 15. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials at the opposite sides of the shoe bottom simultaneously upon relative movement of the shoe support and the rolls lengthwise of the shoe, arms supporting the different 55 rolls and mounted for swinging movements 60 relative to each other heightwise of the shoe.
- 65 16. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials at the opposite sides of the shoe bottom simultaneously upon relative movement of the shoe support and the rolls lengthwise of the shoe, said rolls being mounted for movements 65 relatively to each other under control of the shoe and being adjustable as a unit about an axis extending lengthwise of the shoe to position them in proper relation to the shoe bottom.
- 70 17. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials at the opposite sides of the shoe bottom simultaneously upon relative movement of the shoe support and the rolls lengthwise of the shoe, said rolls being mounted for 75 movements relatively to each other under control of the shoe, a roll carrier supporting said rolls and adjustable about an axis extending lengthwise of the shoe to position the rolls in proper relation to the shoe bottom, and means for holding the roll carrier against movement about said axis during the operation of the rolls on the shoe.
- 75 18. In a machine for pressing the bottoms of welt shoes after attachment of the welt but before the outsole is applied, the combination with a shoe support, of rolls arranged to operate respectively at the opposite sides of the shoe bottom to apply pressure progressively to the shoe inseam materials at the opposite sides of the shoe bottom simultaneously upon relative movement of the shoe support and the rolls lengthwise of the shoe before the outsole is placed on the shoe, each of said rolls being yieldable relatively to the other in response to pressure of the shoe upon it, and automatic means for effecting a comparatively long relative movement of said shoe support and rolls to cause the rolls to traverse the shoe bottom from the toe end substantially to the heel-end portion, then comparatively short relative movements to cause the rolls to traverse the shank portion repeatedly, and then a comparatively long relative movement to cause the rolls to return to the toe end of the shoe.
- 80 19. In a machine for pressing the bottoms of welt shoes after attachment of the welt but before the outsole is applied, the combination with a shoe support, of rolls arranged to operate respectively at the opposite sides of the shoe bottom to apply pressure progressively to the shoe inseam materials at the opposite sides of the shoe bottom simultaneously upon relative movement of the shoe support and the rolls lengthwise of the shoe before the outsole is placed on the shoe, spring means against the resistance of which said rolls are yieldable relatively to each other both heightwise of the shoe and widthwise 85

tively to each other heightwise of the shoe, means for holding the rolls with their axes in fixed relation to said arms throughout the operation of the rolls on the shoe, and separate springs arranged to act respectively on the different arms to press the rolls upon the inseam materials and each adjustable as to stress independently of the other.

90 16. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials at the opposite sides of the shoe bottom simultaneously upon relative movement of the shoe support and the rolls lengthwise of the shoe, said rolls being mounted for movements relatively to each other under control of the shoe and being adjustable as a unit about an axis extending lengthwise of the shoe to position them in proper relation to the shoe bottom.

95 17. In a machine for pressing the bottoms of welt shoes after attachment of the welt but before the outsole is applied, the combination with a shoe support, of a pair of rolls arranged to operate respectively at the opposite sides of the shoe bottom before the outsole is placed on the shoe to apply pressure progressively to the shoe inseam materials at the opposite sides of the shoe bottom simultaneously upon relative movement of the shoe support and the rolls lengthwise of the shoe, said rolls being mounted for movements relatively to each other under control of the shoe, a roll carrier supporting said rolls and adjustable about an axis extending lengthwise of the shoe to position the rolls in proper relation to the shoe bottom, and means for holding the roll carrier against movement about said axis during the operation of the rolls on the shoe.

100 18. In a machine for pressing the bottoms of welt shoes after attachment of the welt but before the outsole is applied, the combination with a shoe support, of rolls arranged to operate respectively at the opposite sides of the shoe bottom to apply pressure progressively to the shoe inseam materials at the opposite sides of the shoe bottom simultaneously upon relative movement of the shoe support and the rolls lengthwise of the shoe before the outsole is placed on the shoe, each of said rolls being yieldable relatively to the other in response to pressure of the shoe upon it, and automatic means for effecting a comparatively long relative movement of said shoe support and rolls to cause the rolls to traverse the shoe bottom from the toe end substantially to the heel-end portion, then comparatively short relative movements to cause the rolls to traverse the shank portion repeatedly, and then a comparatively long relative movement to cause the rolls to return to the toe end of the shoe.

105 19. In a machine for pressing the bottoms of welt shoes after attachment of the welt but before the outsole is applied, the combination with a shoe support, of rolls arranged to operate respectively at the opposite sides of the shoe bottom to apply pressure progressively to the shoe inseam materials at the opposite sides of the shoe bottom simultaneously upon relative movement of the shoe support and the rolls lengthwise of the shoe before the outsole is placed on the shoe, spring means against the resistance of which said rolls are yieldable relatively to each other both heightwise of the shoe and widthwise

of the shoe in response to pressure of the shoe upon them, and automatic means for effecting a comparatively long relative movement of said shoe support and rolls to cause the rolls to 5 traverse the shoe bottom from the toe end substantially to the heel-end portion, then comparatively short relative movements to cause the rolls to traverse the shank portion repeatedly, and then a comparatively long relative movement 10 to cause the rolls to return to the toe end of the shoe.

20. In a machine for pressing the bottoms of welt shoes after attachment of the welt but before the outsole is applied, the combination 15 with a shoe support, of rolls arranged to operate respectively at the opposite sides of the shoe bottom to apply pressure progressively to the shoe inseam materials at the opposite sides of the shoe bottom simultaneously upon relative 20 movement of the shoe support and the rolls lengthwise of the shoe before the outsole is placed on the shoe, each of said rolls having a shoe-pressing face curved widthwise of the shoe and each roll increasing progressively in diameter 25 toward its outer end, spring means arranged to urge said rolls heightwise of the shoe toward the shoe bottom and also inwardly over the shoe bottom lengthwise of their axes, and automatic means for effecting a comparatively long relative 30 movement of said shoe support and rolls to cause the rolls to traverse the shoe bottom from the toe end substantially to the heel-end portion, then comparatively short relative movements to cause the rolls to traverse the shank 35 portion repeatedly, and then a comparatively long relative movement to cause the rolls to return to the toe end of the shoe.

21. In a machine for pressing the bottoms of shoes, the combination with a shoe support, of 40 rolls arranged to operate respectively at the opposite sides of the shoe bottom to apply pressure progressively to the shoe bottom upon relative movement of the shoe support and the rolls lengthwise of the shoe, and means supporting 45 said rolls for bodily swinging movements heightwise of the shoe relatively to each other in the shoe-pressing operation to permit them to assume relative positions determined by the contour of the shoe, the rolls being adjustable as a unit about an axis extending lengthwise of the 50 shoe.

22. In a machine for pressing the bottoms of shoes, the combination with a shoe support, of 55 rolls arranged to operate respectively at the opposite sides of the shoe bottom to apply pressure progressively to the shoe bottom upon relative movement of the shoe support and the rolls lengthwise of the shoe, arms carrying said rolls and mounted for swinging movements heightwise of the shoe relatively to each other in the shoe-pressing operation, means for holding the rolls with their axes in fixed relation to the arms throughout the operation of the rolls on the shoe, and spring means arranged to act on said 60 arms to urge the rolls toward the shoe bottom and yieldable to permit the rolls to assume different relative positions determined by the contour of the shoe.

23. In a machine for pressing the bottoms of 70 shoes, the combination with a shoe support, of rolls arranged to operate respectively at the opposite sides of the shoe bottom to apply pressure progressively to the shoe bottom upon relative movement of the shoe support and the rolls 75 lengthwise of the shoe, arms carrying said rolls

and mounted for swinging movements heightwise of the shoe relatively to each other in the shoe-pressing operation, a member adjustable heightwise of the shoe and on which the arms are thus mounted, and separate springs arranged to act 5 respectively on the different arms to urge the rolls toward the shoe bottom and each independently adjustable as to stress.

24. In a machine for pressing the bottoms of shoes, the combination with a shoe support, of rolls 10 arranged to operate respectively at the opposite sides of the shoe bottom with their axes extending widthwise of the shoe to apply pressure progressively to the shoe bottom upon relative movement of the shoe support and the rolls lengthwise of the shoe, and means supporting said rolls for bodily swinging movements widthwise of the shoe relatively to each other in the shoe-pressing operation to permit them to assume relative 15 positions determined by the contour of the shoe. 20

25. In a machine for pressing the bottoms of shoes, the combination with a shoe support, of rolls arranged to operate respectively at the opposite sides of the shoe bottom with their axes extending widthwise of the shoe to apply pressure 25 progressively to the shoe bottom upon relative movement of the shoe support and the rolls lengthwise of the shoe, said rolls being of greater diameter at their outer ends than at their inner ends, arms carrying said rolls and mounted for 30 swinging movements widthwise of the shoe relatively to each other, and spring means tending to swing said arms inwardly toward each other while permitting them to be forced apart by wedging action of the shoe on the rolls. 35

26. In a machine for pressing the bottoms of shoes, the combination with a shoe support, of rolls arranged to operate respectively at the opposite sides of the shoe bottom to apply pressure 40 progressively to the shoe bottom upon relative movement of the shoe support and the rolls lengthwise of the shoe, and means supporting said rolls for bodily swinging movements relatively to each other both heightwise and widthwise of the shoe in the shoe-pressing operation 45 to permit them to assume relative positions determined by the contour of the shoe.

27. In a machine for pressing the bottoms of shoes, the combination with a shoe support, of 50 rolls arranged to operate respectively at the opposite sides of the shoe bottom to apply pressure progressively to the shoe bottom upon relative movement of the shoe support and the rolls lengthwise of the shoe, arms carrying said rolls and mounted for swinging movements relative- 55 ly to each other both heightwise and widthwise of the shoe in the shoe-pressing operation, and spring means controlling said arms and arranged to press the rolls upon the shoe bottom heightwise of the shoe and also to urge them inwardly toward each other while permitting them to assume relative positions determined by the contour of the shoe.

28. In a machine for pressing the bottoms of shoes, the combination with a shoe support, of 60 rolls arranged to operate respectively at the opposite sides of the shoe bottom with their axes extending widthwise of the shoe to apply pressure 65 progressively to the shoe bottom upon relative movement of the shoe support and the rolls 70 lengthwise of the shoe, arms carrying said rolls and mounted for swinging movements widthwise of the shoe, and spring means arranged to maintain said arms initially in predetermined positions with the rolls properly positioned laterally 75

of the toe end of the shoe and against the resistance of which both arms may be swung simultaneously in one direction or the other widthwise of the shoe.

- 5 29. In a machine for pressing the bottoms of shoes, the combination with a shoe support, of rolls arranged to operate respectively at the opposite sides of the shoe bottom to apply pressure progressively to the shoe bottom upon relative movement of the shoe support and the rolls lengthwise of the shoe, arms carrying said rolls and mounted for swinging movements widthwise of the shoe, spring means tending to swing said arms inwardly toward each other and yieldable to permit the rolls to assume different relative positions determined by the contour of the shoe, and additional spring means controlling said arms and arranged to insure the return of both of them to predetermined positions widthwise of the shoe after the operation of the rolls on the shoe.

30. In a machine for pressing the bottoms of shoes, the combination with a shoe support, of rolls arranged to operate respectively at the opposite sides of the shoe bottom to apply pressure progressively to the shoe bottom upon relative movement of the shoe support and the rolls lengthwise of the shoe, arms carrying said rolls and mounted for swinging movements relatively to each other heightwise of the shoe, members on which the arms are thus mounted, said members being mounted to swing with the arms widthwise of the shoe, springs controlled by said members and arranged to act on the arms to press the rolls upon the shoe bottom heightwise of the shoe, and additional spring means associated with said arms and members and tending to urge the rolls inwardly toward each other while permitting them to be forced apart by action of the shoe thereon.

- 40 31. In a machine for pressing the bottoms of shoes, the combination with a shoe support, of rolls arranged to operate respectively at the opposite sides of the shoe bottom to apply pressure progressively to the shoe bottom while rotated

5 by the shoe upon relative movement of the shoe support and the rolls lengthwise of the shoe, automatic means for effecting such relative movement of the shoe support and the rolls, said rolls being of greater diameter at their outer ends than at their inner ends and being curved lengthwise of their axes at their inner ends, and means for positioning said rolls initially with their inner ends in contact with each other for operation all across the end of the toe, said means being yieldable to permit the rolls thereafter to be forced apart by wedging action of the fore part of the shoe thereon.

10 32. In a machine for pressing the bottoms of shoes, the combination with a shoe support, of rolls arranged to operate respectively at the opposite sides of the shoe bottom to apply pressure progressively to the shoe bottom upon relative movement of the shoe support and the rolls lengthwise of the shoe, arms carrying said rolls 20 and mounted for swinging movements relatively to each other widthwise of the shoe, and spring means controlling said arms and arranged to position them initially with the inner ends of the rolls in substantially contiguous relation to each 25 other, said spring means being yieldable to permit separation of the rolls by the action of the shoe thereon.

33. In a machine for pressing the bottoms of shoes, the combination with a shoe support, of 30 rolls arranged to operate respectively at the opposite sides of the shoe bottom to apply pressure progressively to the shoe bottom upon relative movement of the shoe support and the rolls lengthwise of the shoe, arms carrying said rolls 35 and mounted to swing relatively to each other heightwise of the shoe, a member carrying said arms and also mounted to swing heightwise of the shoe, a spring arranged to act on said member to urge the rolls toward the shoe bottom, and 40 additional springs arranged respectively to control said different arms and thus also to urge the rolls toward the shoe bottom.

JAMES P. FREDERICKSEN. 45
